ANDREW THOMA, OF CAMBRIDGE, MASSACHUSETTS, ASSIGNOR TO NORTH. AMERICAN
CHEMICAL COMPANY, OF NEW YORK, N. Y., A CORPORATION OF MAINE.

MACHINE FOR FILLING THE BOTTOMS OF SHOES.

1,113,381.

Specification of Letters Patent.

Patented Oct. 13, 1914.

Original application filed January 3, 1907, Serial No. 350,588. Divided and this application filed April 2, 1912. Serial No. 688,114.

To all whom it may concern:

Be it known that I, ANDREW THOMA, a citizen of the United States, and resident of Cambridge, county of Middlesex, and State of Massachusetts, have invented an Improvement in Machines for Filling the Bottoms of Shoes, of which the following description, in connection with the accompanying drawings, is a specification, like letters on the drawings representing like parts.

This application is a division of my application Ser. No. 350,588, filed January 3, 1907, and is a power machine for filling the bottoms of shoes with shoe filler, being specially adapted to the normally semi-plastic, tough, elastic filler such as is disclosed in my Patent No. 832,002, of September 25, 1906, although not restricted thereto. The most common means of applying the said patented filler to shoe bottoms is that shown in U. S. Patent No. 808,227 of December 26, 1905, which requires that the filler shall be heated in order to render it sluggishly flowing or plastic and then the operator lifts small portions with a spatula or knife, one hand being required for handling the latter while the other manipulates the shoe.

My present invention aims to do away with these objectionable features, leaving the operator at liberty to use both hands in supporting and manipulating the shoe, and also preferably doing away with the disagreeable presence of heat, and at the same time affording means for filling shoes with far greater speed than is possible by the semi-hand method above referred to.

In carrying out my invention when used in connection with the above specified patented filler, I preferably provide mixers which serve to prepare the filler material in a preliminary way, and a forced feed (which when used in connection with said preferred kind of filler acts also as a friction heating device to render the filler plastic without the presence of extraneous steam pipes or other heating means), and a co-operating gate and controlling device located in the outlet or nozzle of the machine, under the control of the operator, for co-operating with the forcing mechanism to compel the instant delivery of the filler under pressure in exactly the amount required for the given shoe bottom in the hands of

the operator. Also adjacent the delivery opening I provide a presser or packing tool which operates to pack, spread and level the filler in the shoe cavity so that it is properly embedded therein under suitable pressure.

The type of filler mentioned is of a coarse granular nature, usually containing chunks or small angular pieces of ground or chopped cork which are normally stuck solidly together with a cementitious binder, and when softened by heat for the purpose of being laid or deposited in layer-like form in the shoe-bottom cavity, the filler requires to be compacted and unified or reunited and stuck together compactly, but, because of the angular chunks of cork and the extremely sticky character of the binder, the laying-tool tends to roll the cork granules out of position and become smeared with the binder so as to be liable to drag the filler out of the shoe as the tool is smoothed over the filler.

One important feature of my invention therefore resides in providing means for preventing this dislodgment of the filler and for insuring this unifying, packing, condensing, and sticking-together process. I have succeeded in adapting the ironing principle or smoothing and leveling tool to this end, and my invention in this particular resides, not in the molding tool *per se*, but in providing such a tool with a short jogging and rapidly reciprocating movement, in connection with means for rendering it unattractive to the filler, as by smearing its surface with a soapy solution.

A further feature of my invention which is also essential to this chunky, peculiar or special sticky filler, is based upon my discovery that, notwithstanding the slow, set character of the filler whereby it becomes exceedingly difficult to get it started into proper movement when once compacted and permitted to stop and set, this same sluggish filler, if kept in continuous motion, can be discharged at any time instantly through the delivery orifice,—because it will be understood that for practical purposes in filling shoes at high speed, as required in modern shoe factories, the filler must be under such control that it can be instantly delivered into the shoe when the shoe is presented, and instantly stopped when the proper amount has been deposited in the

shoe. Accordingly, this feature of my invention resides in providing, in connection with the continuous forward-feeding and forcing means, such mechanism or construction as will permit and produce a flow of this chunky, granular, dough-like, sticky filler-mass at all times, whether the filler is being discharged at the delivery orifice or not. This feature is essential to the success of the machine, and I regard it as the most important feature of my invention and as radically new as a means which makes it possible to handle this stiff, sticky, chunky dough with practicable speed. Under some 15 conditions and especially with other fillers (the old rubber-cement filler, for instance), this instant-delivery may be accomplished by other mechanism employing simply the forcing feature when ejecting the filler in 20 connection with the manual control, but not necessarily operating continuously.

Various features of my invention are of 25 importance and practical value, apart from the others, all of which will be more definitely apparent in the claims; and the invention will be more fully understood from the following description, taken in connection with the accompanying drawings, in 30 which I have illustrated one embodiment of the invention.

In the drawings, Figure 1 is a central vertical sectional view of my preferred machine; and Fig. 2 is an enlarged sectional detail of the filler delivering device.

For simplicity of presentation and clearness of understanding I have shown the body of the machine as a single casting 1 whose hollow inside constitutes a filler chamber (or container for handling the 40 filler) containing an upper filler receptacle 2, a somewhat narrowed filler receiving chamber or reservoir 3, and a filler feed chamber 4 terminating in a filler delivery passage or discharge end or nozzle 5 having a delivery orifice. In the feed chamber, and preferably directed toward said nozzle and terminating adjacent thereto, I provide means for forcing the filler forward, and as herein shown in the more complete embodiment of 45 the machine, I mount additional means for creating considerable friction with relation to the filler material, and also I preferably provide preliminary means for mixing or disintegrating the filler thereby supplementing the friction action and the forced feeding movement in getting the filler into proper plastic condition, without the use of steam or extraneous heat, for being deposited in a shoe bottom cavity. Preferably the 55 mixing and grinding or disintegrating device and the friction producing mechanism are separate although coöperating, the disintegrating and mixing device being herein indicated at 6. Beneath this is the forced feed device shown as a worm or conical

fluted shaft 7 which screws the material forward with considerable resistance and yet is so shaped that it permits more or less slipping of the material, thereby increasing the frictional action on which I depend to a 70 considerable extent for fluidifying the filler composition (when my invention is carried out without the aid of extraneous heat except possibly to heat the machine at the beginning, or to hasten the fluxing or melting of the filler at the start.) 75

The disintegrator or mixer 6 has claw members or knives 8 and deflector blades 9, in the machine of the drawings, which engage a body 10 of the filler material in the 80 hopper or receptacle 2, although any other form of device may be employed within my invention for tearing apart and clawing off the filler loaf or body 10 and then commingling and mixing or agitating the fragments, the purpose being to bring about a finely divided and thoroughly mixed condition of the filler so that it will be, to a large extent, in condition for application to the shoe bottom. As herein shown, the 85 shaft of the friction feed device 7 is provided with fast and loose power pulleys 12, 13 and a driving gear 14 meshing with a pinion 15 on the shaft 16 of the disintegrator and mixer. At the opposite end of 90 the latter shaft I provide a spur gear 17 meshing with a smaller pinion 18 on a shaft 19 provided with a cam wheel 20 for rapidly reciprocating a link 21 extending centrally 95 from a transverse shaft 22, at whose opposite ends are swing rods 23 (only one being herein shown), pivoted at 24 respectively at the opposite sides of the machine and supporting at their lower ends a laying or 100 packing and spreading device 25 for compacting and unifying and sticking together compactly the granular filler into sheet-like or leaf-like form and leveling down or smoothing or pressing the filler firmly into all the crevices of the shoe bottom. This 105 laying device 25 performs the same functions as the superheating roll of the above mentioned Patent No. 808,227 excepting that it accomplishes my purpose without heat, does not rotate, and smooths or levels down the filler more quickly and accurately, due 110 to its extremely rapid short back-and-forth movement. The back-and-forth movement is so rapid that the succession of short smoothing packing motions causes the filler 115 to be laid or smoothed and pressed down flat into the shoe-bottom almost perfectly, as the shoe is simply drawn back from the machine in contact with said laying device. While the latter may be prevented from sticking to the filler by heat if desired, or 120 by any other means, I prefer to accomplish the purpose by maintaining the engaging side thereof coated with a thin film of repellent liquid, such as oil or soapy water. 125

As herein shown, I have provided a pocket 26 containing a supply of soapy water of a thin jelly-like consistency capable of jarring or oozing through perforations 28 provided 5 for the purpose in the bottom of the pocket 26, so that as the soapy water or other repellent substance oozes or drops through the openings 28, it is scraped or cut off by the adjacent edge of the rapidly moving laying 10 device 25 in sufficient quantity to maintain the under side thereof constantly coated or lubricated with this repellent material. This effectually prevents the filler from sticking to the device 25 without interfering with 15 the effective laying function of the latter. This unifying or laying and packing and spreading device 25 is preferably mounted in a recess or upward jog of the casting so that its lower surface is slightly below the 20 level of the orifice or discharge opening or mouth in which the valve 31 works, so that the adjacent bottom surface of the casting constitutes means tending to direct the forward movement of the shoe-bottom, as the 25 latter is pulled forward by the operator, into engagement with the reciprocating device 25, said directing means also tending to limit the shoe-bottom to such a movement and position with relation to said unifying and 30 compacting member 25 as to receive a light pressure from said member, and yet the construction and relation of parts is such that the operator has both of his hands left free to manage the shoe, and, when desired, to 35 enable the operator to press the shoe forcibly with both hands against the member 25 for leveling and packing the filler into the cavity of the shoe-bottom. This freedom of movement and operation on the part of 40 the operator will be pointed out more at length hereinafter. As the subdivided filler material is forced forward by the feed screw 7 toward the delivery end 5, it is preferably compelled to pass through a coarse screen 45 or subdividing plate 29 for rendering the filler still more plastic and free flowing by the friction of the filler in passing through the holes of the plate. If the filler is not being deposited in a shoe at the moment, it 50 passes thence through a channel 30 back to the rear end of the feed chamber, the idea being to keep the filler in motion and prevent its setting and clogging as already explained. This is the most important feature 55 of my invention, and I intend to cover the same herein generically as the means which renders it possible to handle this coarse, chunky, stiff, sticky filler with speed. In fact, without providing for the continuous 60 movement of the filler irrespective of whether it is being delivered from the machine or not, it is necessary to stop the screw or feeding device after each shoe-filling operation, and there is then extreme liability 65 of bursting the machine when the screw is started again for filling the next shoe. This would not only make the operation slow, but the tenacious, gummy, chunky nature of the filler renders it entirely impracticable to handle filler by continually starting and 70 stopping the feeding screw. Even when used with heat (for rendering the filler fluid) it is impracticable to use the screw alone, but I have found that all the difficulties disappear by simply providing either 75 an auxiliary passage or channel such as 30, or other adjacent cavity or space for the deflection and return of the filler in a continuous flow, and then keeping the screw turning all the time. Besides the sticky, 80 compact nature of the filler, the problem is rendered still more difficult by the resilient or compressible and rebounding, tough, dense character of the cork which constitutes the chunk-like or granular portion of 85 the filler. But by combining the screw, turning continuously in the same forward-feeding direction, and the adjacent provision for the return flow of the filler, I have discovered that this cork filler can be han- 90 dled perfectly. I make this explanation in order that my invention may not be restricted to the passage 30 *per se* but may be understood to include provision of any kind whereby the forwardly pressed or fed filler 95 may be enabled to get back again or have a return flow so as to permit the continuous movement of the filler-mass within the machine, whether the nozzle is closed or open. By this means I am sure always to get a 100 prompt instant delivery when required, as the filler is not merely kept in proper condition by its constant movement, but it is always ready for delivery, whereas if it were permitted to stop, there would be a mo- 105 mentary sluggishness to overcome, due to its extremely sticky and compact nature. At the mouth of the delivery end, I provide a regulator and filler-ejector in the form of a slide 31, shown as normally held forward in 110 closing position by a spring 32 and operated by a bell crank 33 and foot lever 34, said slide having a valve-plate or filler actuator 35, in position to close or partially close the channel 30 according as the slide is entirely 115 opened or only partially opened. This plate 35 thus compels the instant deflection of the moving stream of filler material, so that it must deliver under pressure into the shoe- 120 bottom cavity instantaneously and properly when the slide is opened. In operation a complement of filler material is placed in the receptacle portion 2 of the machine and is automatically disintegrated and comminuted as the parts rotate in 125 the direction of the arrow. As the mass is disintegrated and drops into the receiving chamber or reservoir it is continually churned and mixed. Meanwhile the partially prepared filler is fed forcibly forward 130

4

by the feed worm or screw 7, whose friction serves not only to forward the filler, but to further soften it, the final softening thereof being effected and completed by the forcing of the partially softened filler through the screen or perforated diaphragm 29 (which is not used when other heating means, such as steam, is used). The flow of the filler is continuous whether the machine is filling shoes or not, and while I prefer to provide the separate channel or passage 30 therefor it will be understood that I am not restricted to having this passage thus separated from the main chamber, as all that is necessary, so far as the mere feeding of the filler is concerned, is that there shall be provided space or room enough to permit the filler to return back to the upper portion of the filler chamber whenever the nozzle is closed. This provision of means for permitting the escape of the filler away from the delivery end or nozzle of the machine when said nozzle is closed is essential and of the first importance when the machine is delivering filler of the particular kind first mentioned, *i. e.* the chunky, stiffly coherent, sticky cork-filler, because otherwise said filler would simply pack harder and harder into the nozzle and quickly render the machine inoperative. So I regard the provision of means for permitting the continuous flow and movement of the filler as an important feature of the invention. This means and the coöperating filler-moving mechanism constitute means for transporting the filler in the special way explained.

When the gate or slide valve 31 is closed the filler passes back through the channel 30 and so around continuously, being always ready however because already in motion and in the proper direction and kept actively fluid and preventing from setting to fill a shoe the instant the operator is ready. When ready, the operator, with a shoe properly supported and presented, or, as herein and preferably provided for, firmly held in both hands, if desired, places it beneath the nozzle and then depresses the treadle rod 34, so as to open the valve slide 31 and permit a thin ribbon or flat stream of the filler to flow out onto the shoe. He regulates the thickness of this ribbon by the extent to which he opens the outlet-governing valve 31. The opening movement of said gate or valve 31 simultaneously brings the valve plate or filler actuator 35 into operation so that it compels the filler stream to flow downward out of the nozzle instead of passing through the way or by-pass 30. This member 35 continues to compel the filler to move down under pressure into the shoe bottom cavity as long as the slide valve 31 is held back, but the instant that the latter is permitted to close the delivery opening, the member 35 opens the passage 30 and permits the filler

to be deflected around to the upper end of the chamber 4 again. The instant the shoe is filled, the operator permits the valve 31 to close and quickly pulls the shoe toward himself in contact with the laying device 25, which smooths and compacts the filler into the shoe bottom cavity as desired. This filler is of a granular nature containing chunks of chopped or comminuted cork which, when the filler is in the sluggishly flowing plastic condition necessary for delivery to the shoe-bottom cavity, is somewhat loosely held together by the binder, so that it would not stick permanently to the shoe-bottom cavity nor hold together in leaf-like or sheet-like layer form if left in the condition in which it is delivered into the cavity. To make it stick together in proper sheet-like or layer form and to make it adhere tenaciously to the leather of the bottom cavity, it is necessary to compact it by a relatively light pressure, and I have found that superior results are secured by applying this light pressure, not by one long relatively slow sweep or movement of the tool over the heap of filler, but by giving to the tool a jogging or rapid reciprocating movement of very short amplitude, under such conditions that the filler is prevented from sticking to the tool and also from being pushed or pulled forward by the tool and from being dragged out of the bottom cavity. The tool 25 and its operating mechanism I have found admirably adapted for accomplishing this purpose. Preferably said tool 25 projects freely into space, the machine providing a free open space beneath the tool to enable the operator freely to manipulate the shoe as required for proper leveling and packing of the filler therein. It is to be borne in mind that this process is not a molding process primarily, but is a packing, unifying, condensing and sticking-together process, made necessary by the peculiar character of the filler and its special condition at the moment of laying or placing in the shoe-bottom cavity. All this is accomplished with great rapidity and ease by the operator. There is no fatigue in laying the filler with the laying device as the operator simply pulls the shoe up against said device with both hands and then straight forward toward himself, the rapid back and forth reciprocating movement of the laying device sticking the filler compactly and condensing or reuniting it into leaf-shape, while working the filler down compactly and smoothly and yet almost imperceptibly into the properly laid and level position in the shoe bottom cavity.

Besides the advantages already mentioned of being able to use the filler without melting it by extraneous heat, the speed of my present machine is likewise an important feature, as the operator soon learns to gage

the delivery rapidly and accurately so that he can fill the shoes as quickly as he can handle them. The operator not only has both hands to devote to the shoe, but is 5 without the fatigue and delay of being obliged to select portions of the filler and lift it up into the shoe from the pot as in the above mentioned previous apparatus.

While for convenience I have adapted my 10 machine to the loaf or package form of the filler, I wish it understood that I am not limited thereto, as my invention includes broadly the mixing or churning and preparing of the ingredients to a fairly consistent 15 state for being leveled into a shoe at the time of use, and also embraces broadly the provision of means for mechanically fluidifying or rendering sufficiently plastic a normally stiff filler to permit its being laid in a 20 shoe bottom. My mechanism renders it unnecessary to bring about a state of high fluidity as a more sluggish condition is practicable because of the fact that the machine itself forces the material into a thin 25 layer independently of the exertions of the operator, and the laying or pressing device is especially adapted to mold the filler cold.

Of course, it will be understood that various 30 of the separate elements or features of my invention may be used with the hot process if desired, and that I am not limited in all cases to the relations of parts herein preferred, nor to the kind of filler principally referred to. The soapy solution for 35 the reciprocating packing device is preferable, although various kinds of oily coatings or heat may be used. A vibrating or reciprocating filler-laying motion is of advantage, however whether the tool is hot or 40 cold, as it materially saves the time and strength of the operator.

The rubbing and mixing of the integral 45 portions of the hacked filler create a softening of the material akin to heating, but without heat, and the further subdividing and continuous flow through the machine 50 produces a smoother and nicer consistency than is feasible with heat, eliminating all tendency of the heavier ingredients of the 55 composition to settle by gravity at the bottom. This cold process is not only beneficial to the material as to quality in the respect mentioned, but it avoids the extreme liability of overheating and spoiling the filler experienced in the previously patented method. 60 The screw form of feed is especially advantageous as it is compelling to a predetermined pressure and then, for any greater pressure, permits the filler to slip with a frictional heating effect.

While I prefer for many reasons the forms 65 of feeding mechanism, delivery mechanism, and laying or filler-packing mechanism of the drawings, I am particular to state that I regard my invention as broadly novel in the

points mentioned, and I intend this patent to cover any and all forms of mechanical embodiments within the broad idea of means as hereinafter expressed in the claims, considered with reference to this specification. 70

The channel 30 coöperates with the screw feed to lift or pull up the filler at the top as well as to force it upward at the bottom, as the upper end of the screw or worm draws the filler in toward it from the passage way 75 as the latter delivers the filler to it, and keeps this up continuously while the adjacent portion of the filler is being forced downwardly. Other mechanisms may be provided for keeping up this constant flow 80 of the filler down and around up again, but the means shown is best adapted to the end when the friction softening is required. This mechanism for keeping up this continuous flow and rotation of the filler constitutes one means of keeping the filler under continuous and uniform pressure toward the outlet when the latter is closed, so that, when the outlet valve or gate opens, 85 the filler will come out instantly. As already intimated, this instant-delivery of the filler may be accomplished by other forms of mechanism, particularly under other conditions (as for instance when the present kind of filler is rendered fluid by extraneous 90 heat, as distinguished from the friction heating of the preferred form of machine herein), and with other kinds of fillers, and accordingly, as already pointed out and made still more apparent in some of my 95 claims, I do not limit the invention always to the continuous-movement and unremitting-pressure features which are nevertheless made prominent and constitute some of the most important and leading features of 100 the invention in the preferred embodiment of the machine of the drawings. The arrangement of the screw and bottom at an inclination and with the screw approximately in contact with the bottom is also advantageous 105 in facilitating the feed and the softening. 110

Having described my invention, what I claim as new and desire to secure by Letters Patent is:

1. A machine for filling the cavity of a 115 shoe bottom, having, in combination, a reservoir for the filler; a delivery orifice, means for closing said orifice, and means for transporting filler from said reservoir to said orifice, so arranged that when said orifice is 120 closed said transporting means will produce a movement of said filler toward said closed orifice and thence laterally away therefrom and back into position to be again moved forward by such transporting means, the 125 latter being adapted and arranged to handle filler containing chunks of granulated material like comminuted cork.

2. A machine for filling the cavity of a 130 shoe bottom, having, in combination, a filler

chamber provided with a delivery orifice at its lower end, said chamber and orifice co-operating to tend to deliver the filler by gravity, a rotary feed screw for giving the adjacent filler a continuous forward movement, means co-operating therewith arranged to permit the filler to be forced toward said orifice and thence laterally away from adjacent said orifice and back into position to be again forced forward by said feed screw, said screw and co-operating means being adapted and arranged to handle filler containing chunks of granulated material like comminuted cork, and means at said orifice for controlling the delivery of filler into the shoe-bottom cavity.

3. A machine for filling the cavity of a shoe bottom, comprising a filler chamber provided at its lower end with a delivery passage having a delivery orifice to tend to deliver the filler by gravity, means adapted to handle filler material containing chunks of granulated solid material and arranged for maintaining a continuous movement of the filler, including a worm screw extending toward the delivery passage for forcing the filler forward, and means co-operating therewith for deflecting the forced filler from said passage and permitting it to flow back into the chamber, said means directing said flow toward the top of the chamber, and a valve mechanism for controlling the delivery of filler through said orifice.

4. A machine for filling the cavity of a shoe-bottom, comprising a filler chamber for mixed filler of a sluggish, sticky, coherent nature, having a delivery orifice at its lower end, continuously operating power means in said lower end capable of delivering into a shoe-bottom, through said orifice, the required amount of said filler, and controlling means for varying the amount of filler so delivered in accordance with the requirements of a given shoe-bottom constructed and arranged to open and close said orifice, said continuously operating means, said controlling means, and said chamber containing provision and being constructed and arranged to maintain the aforesaid filler which is in the lower end of the chamber under continuous movement and substantially uniform pressure toward said orifice when the latter is closed and also the same when partially or fully open.

5. A machine for filling the cavity of a shoe-bottom, having, in combination, a filler chamber, devices for forcing the filler from said chamber and for packing it into the cavity of said shoe-bottom, and means for actuating said devices.

6. A machine for filling the cavity of a shoe-bottom, having, in combination, a filler chamber, devices for forcing the filler from said chamber and for packing it into the cavity of said shoe-bottom, and means for

giving the packing portion of said devices a plurality of rapid reciprocations for each filling operation.

7. A machine for filling the cavity of a shoe-bottom, comprising a filler chamber for mixed filler containing resilient chunks of granular solid material stuck together with a binder, said chamber having a delivery orifice at its lower end through which the required amount of said filler may be delivered to a shoe-bottom, a unifying and compacting member for packing and leveling said filler into the bottom cavity of the shoe, and means for rapidly reciprocating said member in the direction required for said packing and leveling operation.

8. A machine for filling the cavity of a shoe-bottom, comprising a filler chamber for mixed filler containing resilient chunks of granular solid material stuck together with a binder, said chamber having a delivery orifice at its lower end through which the required amount of said filler may be delivered to a shoe-bottom, a unifying and compacting laying device for leveling said shoe filler in the bottom cavity of a shoe, and means for giving said device rapid short back-and-forth movements for effecting said leveling of said filler.

9. In a machine for handling shoe-bottom filler, a laying device for leveling and packing the filler in the bottom-cavity of the shoe, and lubricating means for automatically maintaining said device smeared with liquid for permitting free movement of the shoe and filler in contact with said device, said device projecting freely into space and said machine having a free open space beneath the device to permit the free manipulation of the shoe as required for proper leveling and packing of the filler therein.

10. In a machine for handling shoe-bottom filler, means for delivering shoe-filler to the bottom cavity of a shoe, and controlling means for regulating the amount of filler delivered, said controlling means being under the control of the operator independently of his hands and the shoe while leaving both hands free to manage the shoe, and bottom laying means adjacent the delivery portion of the machine.

11. In a machine for handling shoe-bottom filler, means for delivering shoe-filler to the bottom cavity of a shoe, and controlling means for regulating the amount of filler delivered, said controlling means being under the control of the operator independently of his hands and the shoe while leaving both hands free to manage the shoe, and bottom laying means adjacent the delivery portion of the machine in position to permit the operator to press the shoe forcibly with both hands against the same for leveling and packing the filler into the said shoe-bottom cavity.

12. In a machine for handling shoe-bottom filler, means for delivering shoe-filler to the bottom-cavity of a shoe, and controlling means for regulating the amount of filler delivered, said controlling means being arranged to be operated by the foot of the operator leaving both hands free to manage the shoe, and bottom laying means adjacent the delivery portion of the machine in position to permit the operator to press the shoe forcibly with both hands against the same for leveling and packing the filler into the cavity of the shoe-bottom.

13. A machine for filling the cavity of a shoe-bottom, comprising a source of filler supply, and means for causing said filler to flow in a continuous stream, including an endless passageway for the flow of the filler, a delivery orifice leading from said passageway, means for controlling said delivery orifice, and a valve for controlling said passageway, said orifice-controlling means and said valve being constructed and arranged to close said orifice by the opening of said passageway and vice versa.

14. A machine for filling the bottom-cavity of a shoe, comprising a chamber for mixed filler of a sluggish coherent nature containing chunks of granular solid material stuck together with a binder, means for mechanically rendering said filler fluid, and delivering means coöperating with said first mentioned means and constructed and arranged for instantaneous opening and instantaneous closing and under the control of the operator, to deliver the cold filler in a thin layer.

15. A machine for filling the bottom-cavity of a shoe, comprising means for handling shoe-bottom filler material containing chunks of granular solid material stuck together with a binder and for delivering said filler material into a shoe-bottom, foot-operated means under the control of the operator capable of instantly opening and instantly closing for regulating the amount of filler so delivered according to the varying requirements of successive shoes, and laying means adjacent the delivery portion of the machine for leveling and pressing the delivered filler into the shoe-bottom.

16. A machine for filling the bottom-cavity of a shoe, comprising means for handling shoe-bottom filler material containing chunks of granular solid material stuck together with a binder and for delivering said filler material into a shoe-bottom, foot-operated means under the control of the operator capable of instantly opening and instantly closing for regulating the amount of filler so delivered according to the varying requirements of successive shoes, and cold laying means adjacent the delivery portion of the machine in the normal path of the shoe to or from said delivering means for

leveling and pressing the delivered filler into the shoe-bottom.

17. A machine for filling the bottom-cavities of shoes, comprising means for supporting a filler loaf, means for tearing away and disintegrating one end of said loaf, means for receiving the disintegrated filler and forcing the same forward under slipping pressure for frictionally fluidifying the filler, means under the control of the operator for delivering the filler into a shoe-bottom cavity, and means for leveling and packing the filler into finished shape in the cavity.

18. A machine for filling the bottom cavities of shoes, comprising a filler supply chamber having a delivery passage at its lower end provided with a delivery orifice, means for opening and closing such orifice, mechanism acting in conjunction with a portion of the walls of such filler supply chamber to fluidify the filler, a by-pass leading from said delivery passage adjacent such orifice back to said filler supply chamber, said mechanism including means for continuously moving filler through part of said filler supply chamber and said delivery passage, and means for deflecting the filler in the delivery passage to the delivery orifice alone or to the delivery orifice and such by-pass.

19. A machine for filling the cavity of a shoe bottom, comprising a filler chamber having an orifice at its bottom end, means adapted to feed filler material containing chunks of granular solid material stuck together with a cementitious binder and for maintaining the filler under continuous pressure adjacent said orifice irrespective of whether the latter is closed or open and in a direction toward said orifice, means co-operating with said pressure-maintaining means to permit the filler adjacent said orifice to keep normally under movement away from said orifice when the latter is closed, and means capable of instantly opening and instantly closing said orifice for regulating the amount of filler delivered into the shoe bottom according to the varying requirements of successive shoes.

20. A machine for filling the cavity of a shoe bottom, comprising a filler chamber having an orifice at its bottom end, means adapted to feed filler material containing chunks of granular solid material stuck together with a cementitious binder and for maintaining the filler under continuous pressure adjacent said orifice irrespective of whether the latter is closed or open and in a direction toward said orifice, coöperating means to permit the filler adjacent said orifice to keep normally under movement transversely of said orifice when the latter is closed, and means located at said orifice and operable independently of the shoe for

permitting the deflection of at least a portion of the said moving filler through said orifice into the shoe bottom according to the requirements of the latter.

5 21. A machine for filling the cavity of a shoe-bottom, comprising a filler chamber having an orifice at its bottom end, mechanism for maintaining the filler fluid and under continuous and approximately uniform 10 pressure adjacent said orifice and in a direction toward said orifice, including coöperating means for permitting the filler adjacent said orifice to maintain normally a movement transversely of said orifice when 15 the latter is closed, and manually controlled means for opening said orifice and instantaneously diverting the flow of the filler into the cavity of a shoe.

22. A machine for filling the cavity of a 20 shoe-bottom, comprising a filler chamber, for mixed filler of a sluggish, sticky, coherent nature containing chunks of granular solid material stuck together with a binder, having a delivery orifice adjacent its bottom, 25 means for opening and closing said orifice and thereby controlling the delivery of filler from said orifice to the shoe-bottom cavity, and means, including continuously operating power mechanism, to keep said filler in said 30 chamber under continuous movement and substantially uniform pressure toward said orifice when the latter is closed and also when it is open, the aforesaid parts being constructed and arranged to force the filler 35 from said delivery orifice in a thin ribbon-like layer adapted in thickness to the depth of said cavity.

23. In a machine of the kind described, a receptacle for mixed filler of a sluggish, 40 sticky, coherent nature, having an orifice, means coöperating with said receptacle and orifice for delivering the required amount of said filler through said orifice into a shoe-bottom, means for unifying and leveling the 45 deposited filler in said shoe-bottom, and mechanism for giving said unifying and leveling means a toeward movement when said shoe-bottom is in operative relation to said unifying and leveling means.

50 24. In a machine of the kind described, a filler supply chamber having an orifice adjacent its bottom, means for opening and closing said orifice, a screw propeller located adjacent said orifice and adapted to operate 55 continuously for forcing the filler toward said orifice, having a lower pitch of the screw adjacent the orifice than farther back on the screw, whereby the speed of movement of the filler is varied as it moves toward the orifice, and means permitting the 60 return flow of said filler in a different path

when the orifice is closed and while the propeller still continues said forcing movement.

25. In a machine of the kind described, a 65 filler supply chamber having a delivery orifice, and manually governed instant-delivery mechanism for delivering filler at the will of the operator and independently of aid from the shoe into a shoe-bottom when the latter is in operative relation to said orifice. 70

26. In a machine of the kind described, a 75 filler supply chamber having a delivery orifice, means for opening and closing the orifice, and coöperating mechanism for forcing a required amount of filler from the orifice into a shoe-bottom, the aforesaid means and mechanism being combined and controlled to coöperate to permit said forcible delivery of the filler at the will of the operator and independently of the aid of the shoe. 80

27. In a machine of the kind described, a 85 filler supply chamber having a delivery orifice, means for opening and closing the orifice, coöperating mechanism for forcing a required amount of filler from the orifice into a shoe bottom, the aforesaid means and mechanism being combined and controlled to coöperate to permit said forcible delivery of the filler at the will of the operator and independently of the aid of the shoe, and a 90 unifying and compacting member located adjacent said orifice in position to lay the filler with required compactness and desired position in the shoe-bottom.

28. In a machine of the kind described, a 95 filler supply chamber having a delivery orifice, combined with continuously operating power mechanism, and manual means coöperating with said power mechanism independently of the shoe for permitting the instant and forcible delivery of filler to a shoe-bottom as desired by the operator. 100

29. In a machine of the kind described, a 105 filler supply chamber having a delivery orifice, means for opening and closing the orifice, and coöperating mechanism for forcing a required amount of filler from the orifice into a shoe-bottom according to the varying requirements of successive shoes, the aforesaid means and mechanism being combined 110 and controlled to coöperate to permit said forcible delivery of the filler at the will of the operator with substantially uniform pressure for successive shoes and independently of the aid of the shoe. 115

In testimony whereof I have signed my name to this specification in the presence of two subscribing witnesses.

ANDREW THOMA.
